UNITED STATES PATENT OFFICE

WILLIAM H. KLOCKE, OF WOODHAVEN, NEW YORK, ASSIGNOR TO THE CLEVELAND GRAPHITE BRONZE COMPANY, OF CLEVELAND, OHIO, A CORPORATION OF OHIO

APPARATUS FOR MAKING BEARINGS

Application filed February 25, 1929. Serial No. 342,511.

The present invention relates to the manufacture of bearings, and its primary object is to provide an apparatus for use in the bending and shaping of flat blanks of stock into annular shells.

In one embodiment, my invention consists of a mandrel or core and forming devices which are adapted to coact with such core in the shaping of blanks suitable for a subsequent circularizing operation; and in another embodiment, such apparatus is so modified that a completely formed shell is produced by a single operation. In both of these embodiments of my invention, the forming devices take the shape of centrally pivoted jaws having means for positively engaging a blank and operating surfaces of the approximate configurations of the mandrels around which such blanks are bent, and the articles which result in each case have end portions which converge towards each other; when the first mentioned apparatus is being employed, such end portions are thus so disposed that a single additional operation will suffice for completing the shell, and when such second mentioned apparatus is being employed a finished shell results from the first operation. It will therefore be apparent that my invention greatly reduces the number of distinct processes which are necessary for the complete formation of bearing shells, and that as consequences of this such shells can be more rapidly and cheaply manufactured.

To the accomplishment of the foregoing and related ends, said invention, then, consists of the means hereinafter fully described and particularly pointed out in the claims; the annexed drawings and the following description setting forth in detail certain means of carrying out the invention, such disclosed means illustrating, however, but one of various ways in which the principle of the invention may be used.

In said annexed drawings:—

Figs. 1 to 3, inclusive, are end elevational views which illustrate one embodiment of my invention and its manner of operation; and Figs. 4 to 6, inclusive, are generally similar views which illustrate three modifications of the disclosure of the preceding figures.

That embodiment of my invention which is shown in the first three figures consists in general of a head 10 and a mandrel 11. The head 10 comprises an upper part 12 which is slidably mounted between the ways or guides 13, and a lower part 14 which is similarly mounted between the ways 15. The mandrel 11 is associated with a support or pedestal 16 and its upper end and side faces define a forming surface 17. At its lower end, the part 14 of the head 10 is provided with the ears or lugs 18, and to these lugs are pivotally connected the links 19. The depending ends of the links 19 are pivotally connected to the formers 20, and at their centers these formers are fixedly pivoted as at 21. As clearly shown in Fig. 3, the inside or forming surfaces 22 of the members 20 have substantially the same shape as the outside surface 17 of the mandrel 11. Centrally, the formers 20 are flattened as at 23, and these flats are arranged for providing the space 24 when the head 10 is in its elevated position. When such head descends, the cams 25 are adapted to engage with the blank being formed. It is to be understood that flat portions 23 and cams 25 in order to be effective must be on both formers. In order to provide for this it is necessary that the hinged connection of the formers must be in the nature of interfitting parts, similar to the dove-tailing at the corners of certain types of wooden boxes, but relatively movable to provide for the hinge action. In this manner the major portion of the strip of metal to be bent will be acted upon by both formers.

The operation of the above described apparatus is substantially as follows. When the head 10 is in its extreme upper position (Fig. 1), a flat blank 26 is positioned between the flats 23 and the top of the mandrel 11. Such head is then moved downwardly by any suitable means (not shown). During this movement, the cams 25 rotate into their locking positions and the outer ends of the blank are bent downwardly and conformed to the mandrel 11 by the members 20. The pivots which connect the links 19 with the lugs 18 and the formers 20 are so arranged that the force exerted by the head 10 when in its lowermost

position will have a component which tends to move the lower of such pivots towards each other. Therefore, all parts of the blank will be compelled to conform to the surface 17 of the mandrel 11 and the finished article will have the shape shown in Fig. 3. When the head 10 is again raised to its uppermost position and the cams 25 again assume their normal positions, the blank will retain its imparted form and is ready to be slid from the mandrel and then circularized.

The modification shown in Fig. 4 differs from the apparatus just described in that the mandrel 27 and the formers 28 are adapted to completely circularize a blank in a single operation. Otherwise, it is the same in construction and operation as the embodiment illustrated in Figs. 1, 2 and 3. In the modification illustrated in Fig. 5, the pivot 29 is not fixed as in the preceding figures, but instead is adapted to push upwardly against the yielding plunger 30. Such plunger is reciprocably mounted within the bore 31 of the head 32, and intermediate its enlargement 33 and the shoulder 34 is a compression spring 35. Its upward motion is limited by the flange 36 and its downward motion is limited by the washer 37, this latter being held in place by the nut 38. The modification illustrated in Fig. 6 differs from the embodiment shown in Figs. 1 to 3, inclusive, in that the links 39 are pivoted at their lower ends to the supplementary formers 40 instead of being directly pivoted to the main formers 41. Such main formers are fixedly pivoted as at 42 and their remote ends pivotally connect with the supplementary formers 40. The lower surface of the mandrel 43 is above the plane of action of the operating ends 44 of the formers 40. Therefore, when the formers 41 have assumed or are about to assume their lowermost positions, any continued downward movement of the head 45 will result in forcing the ends 44 of the formers 40 inwardly and upwardly. This will have the effect of additionally bending the stock being formed and will further insure against any undesired uncoiling when the formers are raised to their initial positions.

The articles produced by the apparatus shown in Figs. 1, 2 and 3, and the articles which result from the operations described in connection with Figs. 5 and 6 may be finished in any desired manner, a preferable practice consisting in placing such articles in the space defined by stationary and movable dies having semi-cylindrical forming surfaces and in then relatively approaching such surfaces in order to form circular shells of the desired diameter and with abutting edges which will remain in contact after this operation has been completed.

Other modes of applying the principle of my invention may be employed instead of the one explained, change being made as re-

gards the means herein disclosed, provided those stated by any of the following claims or their equivalent be employed.

I therefore particularly point out and distinctly claim as my invention:—

1. In apparatus of the class described, a core, formers for coacting with such core, a fixed pivotal connection between such formers, and cam means associated with such connection, said means being adapted to engage and hold a blank positioned between said connection and said core.

2. In apparatus of the class described, a core, formers for coacting with such core, a pivotal connection between such formers, and flat and cam means associated with such connection, said flat means being adapted to form a space between said connection and said core, and said cam means being adapted to engage a blank positioned in such space.

3. In apparatus of the class described, a stationary core, pivoted forming means adapted for coacting with such core, yielding means for urging the adjacent ends of such formers towards said core, and positive means for moving the remote ends of such formers towards said core.

Signed by me, this 21st day of February, 1929.

WILLIAM H. KLOCKE.
